UNITED STATES PATENT OFFICE

2,329,330

HOLE CLEANSING DEVICE

Charles Gilbert Brailey, Port Henry, N. Y., assignor to Sullivan Machinery Company, a corporation of Massachusetts

Application July 31, 1941, Serial No. 404,889

16 Claims. (Cl. 255—50)

This invention relates to hole cleansing devices, and more particularly to devices for removing cuttings formed in a hole during the drilling of the latter.

In the formation of holes in rock, it is customary to effect the removal of the finely divided particles of rock formed by the action of the drill bit on the material at the bottom of the hole, by discharging a fluid at the bottom of the hole through the working instrument, and using this fluid to lift the cuttings and chips from the hole. A liquid or a gaseous fluid may be used for this purpose, but in either case it is important that a substantial velocity of fluid upwards of the hole be maintained. In the drilling of relatively large holes the clearance around the drill steel is likely to be so great that an adequate rate of fluid flow upwards in the hole is very difficult to maintain.

The provision of means for reducing the flow area from the bottom of the hole to the ground level, and the provision of means for augmenting the velocity of flow over that which would be obtained solely as a result of the fluid delivered to the bottom of the hole through the drill bit, will make the cleansing of large holes much more effective and, by reason of the reduced loss of force of blow on a pad of cuttings, will augment the drilling rate.

For the purpose of effecting these aids to hole-cleansing, I propose to provide on the drill rod, at an appropriate distance from the bottom of the hole, a partition-like member of such dimension as largely to prevent the escape of fluid past it up through the hole, and to provide means of relatively smaller diameter than the annular space around the drill rod through which fluid from the bottom of the hole may be discharged. Desirably, means may be associated with the discharge conduit means for augmenting the rate of flow through the latter; and, in a preferred form of the invention, this may take the form of a jet supported by the partition-forming means and fed with fluid under substantial pressure through a conduit independent of the cleaning fluid supply passages in the rod line proper. If desired, the supply means for the jet may also be utilized to supply fluid to a further jet for maintaining turbulence within the space below the partition member.

An object of this invention is to provide an improved hole cleansing device. Another object is to provide improved means for removing loose material from the bottom of a drill hole. Still another object is to provide improved means for

removing loose dry material from the bottom of a drill hole during the drilling of the latter. Still another object is to provide improved means for substantially closing off a space at the bottom of a drill hole, agitating material in this space, and effecting a removal of the material by effecting its entrance into a conduit and discharging it to the surface. Still another object is to provide improved means associated with a drill tool, for maintaining a largely enclosed space of relatively uniform volume at the bottom of a hole during the drilling of the latter, and effecting a discharge of loose material from such space and a delivery of the material to the surface. Still another object of the invention is to provide an improved attachment for a rock drilling apparatus for substantially obstructing the space surrounding the drill rod and providing for a restricted discharge from the space below said attachment. Yet a further object of this invention is to provide an improved device for attachment to a drill rod both providing for the substantial closing off of escape of fluid upwardly past said device and embodying means for effecting a discharge of fluid at relatively high velocity from beneath such device. Other objects and advantages of the invention will, however, hereinafter more fully appear.

In the accompanying drawing there is shown, for purposes of illustration, one form which the invention may assume in practice.

In this drawing:

Fig. 1 is a vertical view of a portion of a drilling mechanism having the invention incorporated therein, parts of the drilling mechanism being shown in section.

Fig. 2 is an enlarged sectional view showing a portion of the improved hole cleansing device and its connection to the drilling mechanism.

Fig. 3 is a horizontal sectional view taken on the plane of the line 3—3 of Fig. 2.

Referring to the drawing, it will be noted that my invention, in its illustrative form, is incorporated in a drilling mechanism of the hammer actuated type, the forward portion of which is indicated at 1. The invention may, however, be employed in drilling mechanisms of the rotary type, or, from certain of its aspects, be used independently of a drilling mechanism. In Fig.

1 there is shown the forward portion of a drill motor 2 which is slidably mounted on a pair of feed cylinders 3 and which is adapted to deliver impact blows to a drilling tool generally designated 4. The motor, whose specific structure need not be illustrated in great detail, includes

a chuck housing 6 held in assembled relation with the other parts of the motor by usual side rods 7, coiled springs 8 and nuts 9. Within the chuck housing 6 is rotatably mounted a chuck sleeve 10 connected, as by clutch teeth at its forward end, to a driver member 12 having usual lugs which are engageable with lugs 14 formed on the shank of the drilling tool 4 for driving the latter. The rear portion of the drilling tool is slidably supported in a usual manner within a chuck bushing 15 suitably secured to the chuck sleeve 10, and the rear end of the drilling tool projects beyond the chuck bushing to receive blows delivered thereto by a striking bar 16 of a hammer piston. Formed on the striking bar are straight grooves 18 cooperating with straight keys on a chuck nut 19 threaded within the chuck sleeve 10 for transmitting rotary movements of the hammer piston to the drilling tool in a manner well understood by those skilled in the art. The forward ends of the feed cylinders 3 are connected by a transverse member 20 carrying a centralizer or guide 21 of a suitable design for the drilling tool support as drill rod 4. Extending longitudinally through the drilling tool is a passage 22, and a conduit 23 extending longitudinally through the striking bar 16 to a space at the rear end of the drilling tool delivers air under pressure from any suitable source to the passage 22 which conducts the air to the bottom of the drill hole. A suitable bit 54 is carried at the bottom of the drill rod. The drilling tool support or drill rod 4 and the bit 54 evidently cooperate or unite to form a drilling tool.

Supported by the drill rod at a point spaced from its forward end is the improved hole cleansing device, generally designated 24. The hole cleansing device comprises a circular disk 25 having a diameter slightly less than that of the hole so that it will not wedge in the hole during the drilling of the latter, and yet large enough so that the clearance around its periphery will be sufficiently small to prevent the escape of substantial quantities of fluid from the bottom of the hole past the disk. The disk is loosely supported by the drill rod in a manner to prevent it from moving longitudinally of the latter but at the same time to permit free rotative movement between the rod and the disk. In this case the support for the disk is provided at the junction of two rod sections 26 and 27 threadedly connected together, as at 28, and includes a shoulder 29 formed on the section 26 and a shoulder 30 formed on the upper end of the section 27, these shoulders having between them an annular groove 31 for receiving the annular portion of the disk surrounding an opening 32 through which the forward end of the rod section 26 extends. The groove 31 is of such width, when the rod sections 26 and 27 are in full threaded engagement, as to provide a loose fit for the disk 25. A small clearance 33 is provided between the wall of the opening 32 in the disk and the periphery of the rod section 26 to permit relative transverse movement between the disk and drill rod. Formed in the disk is a passage 34 communicating at one end with a port 35 opening through the upper surface of the disk, and opening at its other end into a passage 36 extending through the disk as shown in Fig. 2. A flexible conduit or tube 38 is connected in communication with the port 35 by a connecting element 39 threaded into the port, and this tube delivers air under pressure to the passage 34 from any suitable source and under the control

of any suitable devices not shown. Threaded into the end of the passage 34 opening into the passage 36 is a nozzle 40 which extends upwardly a short distance into the passage 36 and discharges along the axis of the latter. A flexible tube 42 is connected by a connecting element 43 to the passage 36 at the upper side of the disk. The cross sectional area of the passage in the tube 42 is made large enough to enable the ready discharge of the cuttings along with the air entering the hole through the passage 22 and the air delivered through the nozzle 40, but small enough to maintain a velocity of flow which will ensure the cuttings being carried along in the flowing column of air. If other flow augmenting means than the nozzle 40 were used, e. g., a vacuum producing arrangement connected to the discharge end of the conduit 42, a modification in the flow area of this conduit might be made if desired or deemed necessary. The bottom of the disk is recessed and is herein preferably made concave, as at 44, in order to reduce eddy currents and to direct material carried upwardly from the bottom of the hole to the passage 36 and the tube 42. At the top of the hole, if desired, a plate 46 may be placed on the surface, and be provided with openings 47, 48 and 49 through which the drill rod and the tubes 38 and 42, respectively, may extend. The openings 48 and 49 are so located as to hold the tubes 38 and 42 from frictional engagement with the walls of the hole, and the upper edges of the holes are rounded at 51 and 52 to reduce wearing of the tubes.

As the piston of the hammer motor is reciprocated to deliver impact blows to the end of the drilling tool through the striking bar 16, the motor is moved along the feed cylinders 3 to bring the drill bit 54 at the forward end of the drilling tool

support into engagement with the material to be drilled. Air under pressure is supplied through the conduit 23 and the passage 22 to the bottom of the hole formed by the drill bit, and any loose material is forced upwardly about the drill rod.

When the hole is still shallow the relatively large area between the wall of the hole and the periphery of the drill rod will not prevent successful discharge of the cuttings to the surface, but as the hole deepens difficulty would be encountered in a hole of substantial size were it not for the fact that the disk 25 on entering the hole largely interrupts the escape of fluid through the bore of the hole so that an adequate discharge rate through the passage 42 may be secured. As previously noted, the cuttings are directed to this passage by the concave lower side 44 of the plate, and the nozzle 40 discharging into the conduit 42 increases substantially the velocity of flow through the latter. As previously noted, additional turbulence of the air within the space below the partition member might be provided for the purpose of maintaining the rock dust and cuttings in suspension by providing an auxiliary jet opening downwardly through the member 25 from the conduit 35. It will be observed that the material carried by the air flowing through the conduit 42 to the surface is not only more effectually and positively discharged due to the much higher velocity of the stream of fluid flowing through this conduit, but also the cuttings may be discharged at any desired point.

From the foregoing description, it will be evident that I have provided an attachment of substantial utility—one particularly beneficial where

relatively large holes are to be drilled, that this attachment secures full efficacy for the fluid delivered to the bottom of the hole in the discharge of the cuttings and augments this fluid in bringing about the discharge of cuttings by providing an auxiliary volume of air moving through the discharge conduit. The attachment is inexpensive and can be made to the drill rod simply by providing, if one is not already present at the desired location, a joint in the drill rod at the desired distance above the bottom of the hole. Where the nozzle 40 is employed no auxiliary means at the surface for the purpose of augmenting the flow through the discharge conduit 42 is necessary.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling mechanism, in combination, a drilling tool, a motor for actuating said drilling tool, and means for removing material from the hole formed by said drilling tool including a conduit, means supported by said tool at a point between the ends of the latter and cooperating with the walls of the hole to provide restricted communication along the walls between the space at the bottom of the hole and the space above said means, and means for connecting said conduit in communication with the space at the lower side of said last mentioned means.

2. In a drilling mechanism, in combination, a drilling tool, a motor for actuating said drilling tool, and means for removing material from a hole formed by said drilling tool including a conduit, a disk supported by said tool at a point spaced from the bottom of the hole, said disk preventing free communication between the spaces at its opposite sides, means for connecting said conduit in communication with the space at the lower side of said disk, and means for effecting passage of material into said conduit and a discharge of the material through the conduit to the surface.

3. In a drilling mechanism, in combination, a drilling tool, a motor for actuating said drilling tool, and means for removing material from a hole formed by said drilling tool including a conduit, a disk supported by said tool at a point spaced from the bottom of the hole, said disk preventing free communication between the spaces at its opposite sides, means for connecting said conduit in communication with the space at the lower side of said disk, and means discharging air under pressure upwardly into the lower end of said conduit for effecting delivery of material from the hole into the conduit and discharging it through the conduit to the surface.

4. In a drilling mechanism, in combination, a drilling tool, means for actuating said drilling tool, and means for removing material from a hole formed by said drilling tool including a conduit supported at one end at a point spaced a substantially uniform distance from the bottom of the hole irrespective of the depth of the latter, means surrounding the lower end of said conduit for substantially obstructing communication between the portions of the hole respectively above and below said conduit surrounding means,

means for delivering air under pressure to the bottom of the hole for agitating the loose material produced by said drilling tool, and means for producing a suction at the lower end of said conduit for promoting the entry of material into the conduit and for effecting discharge thereof through said conduit to the surface.

5. In a drilling mechanism, in combination, a drilling tool, a motor for actuating said drilling tool, and means for removing material from a hole formed by said drilling tool including a material-conducting tube, a disk supported by said tool for substantially closing off a space at the bottom of the hole, means for connecting said tube in communication with said space, and means discharging air under pressure upwardly into the lower end of said material-conducting tube for sucking material from the hole into the tube and discharging it through the tube to the surface, said last mentioned means including a conduit extending into said hole and delivering air under pressure to a passage formed in said disk, and a nozzle for discharging air from said passage axially into the lower end of said material-conducting tube.

6. In a drilling mechanism, in combination, a drilling tool, means for actuating said drilling tool, and means for removing material from a hole formed by said drilling tool including a conduit for conducting material, a disk supported by said tool for substantially closing off a space at the bottom of the hole, means including an opening in said disk for connecting said conduit in communication with said space, means for delivering air under pressure to the bottom of the hole and agitating material in said space, and means for creating a suction at the lower end of said conduit and effecting a withdrawal of material from said space.

7. In a drilling mechanism, in combination, a drilling tool, means for actuating said drilling tool, and means for removing material from a hole formed by said drilling tool including a conduit for conducting material, a disk supported by said tool for substantially closing off a space at the bottom of the hole, means including an opening in said disk for connecting said conduit in communication with said space, means including a passage extending through said drilling tool for delivering air under pressure to the bottom of the hole and blowing loose material upwardly about the tool in said space, and means discharging air under pressure upwardly into the lower end of said conduit for effecting a suction of material from said space into said conduit and a discharge of the material through said conduit to the surface.

8. In a drilling mechanism, in combination, a drilling tool, means for actuating said drilling tool, and means for removing material from a hole formed by said drilling tool including a conduit for conducting material, a disk supported by said tool for substantially closing off a space at the bottom of the hole, means including an opening in said disk for connecting said conduit in communication with said space, means including a passage extending through said drilling tool for delivering air under pressure to the bottom of the hole and blowing loose material upwardly about the tool in said space, and means discharging air under pressure upwardly into the lower end of said conduit for effecting a suction of material from said space into said conduit and a discharge of the material through said conduit to the surface, said last mentioned means in-

cluding a passage in said disk, a conduit extending into said hole and delivering air under pressure to said disk passage, and a nozzle discharging air from said disk passage axially into said material conducting conduit.

9. In an apparatus of the class described, a drilling implement having means for discharging a cleansing fluid therethrough to the bottom of a drilled hole, means supported by said drilling implement a substantially uniform distance above the bottom of the hole irrespective of the depth of the latter for obstructing the bore of the hole, means providing a discharge conduit leading to the surface from the space below said obstructing means, and means for providing a velocity of flow through said conduit means in excess of that which would be produced by the cleansing fluid discharged through the drilling implement.

10. An attachment for bit-carrying drill rods comprising a partition-forming member having an opening through which a drill rod is adapted to extend, having a supply opening for fluid under pressure, having an opening connecting its opposite sides, and having a nozzle connected for supply of fluid thereto from said supply opening and discharging axially of said second opening, said member substantially corresponding in diameter to the diameter of the hole to be formed by a drill bit carried by said drill rod.

11. An attachment for drill rods comprising a partition-forming member having an opening to be traversed by a drill rod and of an external diameter slightly smaller than that of the bit carried by said rods, said partition-forming member traversed by a passage for the delivery of fluid and cuttings from below it to its upper side, said passage proportioned to the volume of fluid to be passing through it to maintain a flow velocity materially higher than prevails in the space below said partition-forming member.

12. In an apparatus of the class described, a drilling tool, means for actuating said drilling tool, and means for removing material from a hole formed by said drilling tool including a conduit, a member supported by said tool at a point spaced from the bottom of the hole, said member cooperating with the walls of the hole to provide a restricted communication between the portions of the hole respectively above and below said member only along the walls of the hole, a concave surface at the lower side of said member, means for connecting said conduit in communication with the space at the lower side of said member, and means for producing a suction within said conduit.

13. In an apparatus of the class described, a drilling tool, means for actuating said drilling tool, and means for removing material from a hole formed by said drilling tool including a conduit, a member supported by said tool at a point spaced from the bottom of the hole, said member cooperating with the walls of the hole to pro-

vide a restricted communication between the portions of the hole respectively above and below said member only along the walls of the hole, a concave surface at the lower side of said member, passage means opening through said concave surface at a point above the lowermost edges of the latter, means for connecting said conduit in communication with said passage means, and means for producing a suction within said conduit.

10 14. A device for removing loose material from a hole comprising, in combination, a member fitting within the hole and cooperating with the walls of the latter to permit a restricted communication between the portions of the hole respectively above and below said member only along the walls of the hole and adapted to move down the hole as the latter deepens so as to be constantly near the bottom of the hole, the lower side of said member being recessed, a conduit connected through the bottom of the recess in communication with the space at the lower side of said member and extending to the top of the hole, and means for producing a suction within said conduit.

25 15. A device for removing loose material from a hole comprising, in combination, a member fitting within the hole and cooperating with the walls of the latter to permit a restricted communication between the portions of the hole respectively above and below said member only along

30 the walls of the hole and adapted to move down the hole as the latter deepens so as to be constantly near the bottom of the hole, the lower side of said member being recessed, a conduit connected through the bottom of the recess in communication with the space at the lower side of said member and extending to the top of the hole, and means including an air supply conduit connected to said member and adapted to enter the hole progressively as said member moves downwardly therein and a nozzle discharging air axially into the lower end of said first mentioned conduit for creating a suction within said conduit.

40 16. Apparatus for removing the cuttings from the bottom of a drill hole comprising a device attached to a drilling implement and adapted to enter the hole being drilled for obstructing the flow of fluid from the bottom of the hole past said device, said device being disposed on said drilling implement a substantially uniform distance from the hole bottom irrespective of the depth of the hole, means for supplying cleansing fluid to the hole bottom below said device to clear the cuttings away from the cutting portion of the drilling implement, and means communicating with the bottom of the drill hole below said device and extending to the ground surface for discharging the cuttings from the bottom of the hole.

60 CHARLES GILBERT BRAILEY.
